Primary Examiner — Mehri F Bajoul

(57) **CLAIM**

The ornamental design for a docking station for handheld game consoles, as shown and described.

DESCRIPTION

1. Docking station for handheld game consoles
1.1 is a front perspective view showing my new design in a closed state;
1.2 is a front elevational view thereof;
1.3 is a back elevational view thereof;
1.4 is a left elevational view thereof;
1.5 is a right elevational view thereof;
1.6 is a top plan view thereof;
1.7 is a bottom plan view thereof;
1.8 is a front perspective view showing the claimed design in an extended state;
1.9 is a bottom perspective view thereof.
FIG. 1.1 is a perspective view of a docking station for handheld game consoles according to a first embodiment with a bracket in storage state, showing my new design; FIG. 1.2 is a front view thereof# FIG. 1.3 is a rear view thereof# FIG. 1.4 is a left side view thereof# FIG. 1.5 is a right side view thereof# FIG. 1.6 is a top view thereof# FIG. 1.7 is a bottom view thereof# FIG. 1.8 is a perspective view of our docking station for handheld game consoles as seen from a front, right and top thereof with a bracket in an extended state# FIG. 1.9 is a perspective view of our docking station for handheld game consoles as seen from a front, left and bottom thereof with a bracket in an extended state; The broken line features depict portions of the docking station for handheld game consoles that form no part of the claimed design.

1 Claim, 9 Drawing Sheets
